FLUTED PLANO-ASPHERIC LENS

Howard A. Schaefer, Lancaster, Ohio, assignor to
Anchor Hocking Corporation, Lancaster, OhioOriginal design application Feb. 25, 1970, Ser. No.
21,604. Divided and this application Sept. 1, 1971,
Ser. No. 177,199

Term of patent 14 years

Int. Cl. D26—06
U.S. Cl. D48—32FIG. 1 is a rear elevational view of a fluted plano-aspHERIC lens showing my new design;

FIG. 2 is a side elevational view of the lens shown in FIG. 2 illustrating the aspheric frontal surface;

FIG. 3 is a front elevational view of the lens shown in FIGS. 1-2; and

FIG. 4 is a cross-sectional view taken through FIG. 1 along the line 4—4 illustrating the planar-ripled rear surface with each of the peripheral flutes to have a spherical segmental cross-section.

This is a division of design application Ser. No. D. 21,604 filed Feb. 25, 1970.

I claim:

The ornamental design for fluted plano-aspHERIC lens, substantially as shown.
